[57] **CLAIM**

The ornamental design for a fitted top sheet, as shown and described.

DESCRIPTION

FIG. 1 is a front elevational view of a fitted top sheet showing our new design;

FIG. 2 is a rear elevational view thereof;

FIG. 3 is a left side elevational view thereof;

FIG. 4 is a right side elevational view thereof;

FIG. 5 is a top plan view thereof; and,

FIG. 6 is a bottom plan view thereof.

The fabric pattern fragmentarily shown in FIGS. 1-6, is understood to extend uniformly throughout the fitted top sheet. The broken lines in FIGS. 1 and 2 represent stitching.
